REMOTE CONTROL SYSTEM

Fernand Pierre Gohorel and Raoul Lafon, Paris,
France, assignors, by mesne assignments, to
Associated Electric Laboratories, Inc., Chicago,
Ill., a corporation of Delaware

Application June 3, 1935, Serial No. 24,762
In France June 12, 1934

14 Claims. (Cl. 179—5.5)

The present invention refers to the remote control of apparatus by currents of voice frequency, and is more particularly applicable to the transmission to a distance of controls or signals between two stations which can be connected together through the medium of automatic or manual switching apparatus, by means of circuits which may or may not be employed for other purposes, such as telephony or teleg-
raphy, for example.

One of the characteristics of the invention resides in a remote control apparatus comprising the following elements: (a) a voice frequency current emitter arranged to send, either automatically or hand operated (keyboard or automatic telephone dial, for example), signals of convenient number and duration; (b) one or more receiving stations each comprising a voice frequency current receiver acting upon a recording apparatus arranged to produce a control or signal according to the code of the signals received; (c) one or more lines, telephonic or otherwise, which can be connected together for the purpose of connecting a transmitting station to a receiving station; (d) means allowing of the putting into play, automatically or not, of the transmitting apparatus when the connection between a receiving station and a transmitting station is established, and this during the time necessary for the transmission of the signals, the connecting lines being rendered available for another use (telephony for example) when the transmission of the signals has been finished.

Another characteristic of the invention lies in a transmitting apparatus such as previously described but arranged to send first the controls necessary for the establishment of the connection between the transmitting and receiving stations, and then the voice frequency current signals intended to produce the control or signal desired at the receiving station.

Another characteristic of the invention lies in the application of the preceding apparatus to the direct connection of a telephone or telegraph transmitting station to a secondary receiving station connected to a secondary exchange over the lines of one or more telephonic or telegraphic networks, either public or private; the transmitting station being arranged to send pulses of voice frequency current over the telephonic or telegraphic connection established by the lines of the network between the transmitting station and the exchange, so as to bring about the orientation of the selectors of the secondary exchange and thus to complete the telephonic or tele-

graphic communication between the transmitting station and the secondary receiving station. The connection of the lines in the network may be established either by means of an operator or by automatic switches, or partly by both of these methods of connection; in the case of automatic connection the transmitter of the transmitting station may be arranged to produce first the establishment of the main connection and then the establishment of the local connection in the secondary exchange.

Another characteristic of the invention lies in an entirely automatic transmitting apparatus arranged to send, first, series of impulses over a telephonic or other line in order to bring about the connection of the latter to a receiving apparatus, and then other series of impulses to allow of the identification at the receiving station of the transmitting station, and finally to receive from the latter a particular communication; the transmitting apparatus being adapted so as only to send the identification impulses when the connection with the receiving station is definitely established. In addition, the said transmitting apparatus may send one or more codes of connection signals to bring about the connection of the transmitting station to one definite receiving station among many receiving stations, and one or more codes of voice frequency signals to record one or more communications at the receiving station; the particular code of connection signals or of voice frequency signals being determined by the nature of the communication to be transmitted.

One further characteristic of the invention lies in the application of an automatic transmitting apparatus such as the above to the automatic communication at a distance of various incidents (theft, fire, etc.). The invention covers in particular, in this case, the use of an apparatus comprising: (a) an automatic transmitting apparatus, such as described above, situated at the transmitting station and capable in case of emergency of being connected to a primary line (telephonic for example) united to a central exchange; (b) a receiver situated at the station where the signal is to be received, and capable of being connected either temporarily or otherwise to a second line (telephonic or otherwise), this second line being capable of direct or indirect connection to the first by one or more exchange centers, the transmitter sending first impulses through the line in order to connect it to the receiving station and then communication impulses so as to establish the identity of the

transmitting station at the receiving station and to record a definite communication.

Also the said apparatus may be arranged so that the connection between the transmitting and receiving stations can be broken automatically as soon as the desired communication has been transmitted, so as to disengage the connecting lines, and to allow the receiving station to receive a communication from another transmitting station; in this case the receiver is associated with one or more recorders which register the communication (after the disengagement of the line) either by visible signals, by marking on a tape, or by both methods simultaneously.

We will now explain the working of different applications of a remote control apparatus in the spirit of the invention, by means of some not exclusive examples, referring to the attached diagrams which represent in

Figure 1, a method of realizing the electric circuit of a transmitting station comprising a transmitter of voice frequency current;

Figure 2, another method of realizing the electric circuit in which a group of transmitting stations use a common voice frequency transmitter;

Figure 3, the electric circuit of a receiving equipment in a secondary exchange, together with a connecting line allowing of direct connection with stations attached to this secondary exchange;

Figures 4, 5, 6, and 7, a method of realizing an automatic transmitting apparatus;

Figure 8, the electric circuit of a receiving station adapted for use in connection with an automatic apparatus.

We will consider first a station such as that of Figure 1, connected by conductors 40 and 41 to conductors 42 and 43 ending in an exchange 39, which may be the case of a subscriber's station connected to a public automatic exchange.

Let us suppose that a person at the said station wishes to enter into direct communication with a station attached to a secondary exchange (such as a private automatic exchange), the said exchange having a receiving equipment like that of Figure 3, and that the communication is to be effected without the intervention of a third person.

The calling subscriber unhooks his handset, and by the operation of the switchhook loops the line at his station.

By operating his calling dial, he then brings about the numerical operation of automatic switches in the public exchange 39, so as to connect with conductors 67 and 68 leading to the secondary exchange, all in accordance with the current practice in automatic telephony.

At the end of the dialling, the final switch or connector in the public exchange 39, Figure 3, sends periodic ringing current over the trunk line conductors 67 and 68. This ringing current is received by the relay 12 in the circuit: conductor 68, armature 111 and its resting contact, armature 191 and its resting contact, condenser 69, relay winding 12, armature 112 and its resting contact, and conductor 67.

On the reception of ringing current during the first ringing period, the relay 12 energizes and remains so during the whole duration of the said period. By its armature 121 and its working contact it closes the circuit of the relay 14: earth, armature 121 and its working contact, armature 132 and its resting contact, the winding of relay 14 and the battery. Relay 14 energizes and by means of its armature 141 and its

working contact prepares its locking circuit through relay 13. When the relay 12 releases at the end of the first ringing period, the relay 13 energizes in series with 14 and prepares the energizing circuit of the relay 16, through its armature 132 and working contact.

On the reception of ringing current the second time, relay 12 responds again and the relay 16 energizes in the circuit: earth, armature 121, working contact of armature 132, armature 152 and resting contact, the winding of relay 16 and the battery. Relay 16 energizes, and, through its armature 161 and working contact, prepares its locking circuit in series with the relay 15. At the end of the second ringing period the relay 12 releases and the relay 15 energizes in series with the relay 16 in the circuit: battery, winding of relay 16, winding of relay 15, armature 161, armature 192, and earth. Through its armature 152 relay 15 breaks the circuit of the armature 121 of relay 12; through its armature 151 and working contact it closes the circuit of the relay 19: conductor 68, armature 111 and its resting contact, armature 151 and working contact, armature 181, armature 201, the upper winding of relay 19, armature 112, to conductor 67.

The line conductors 67 and 68 are now bridged by the relay 19, which has the known effect of stopping the transmission of ringing current by the connector, and the completion of a talking connection from the conductors 40 and 41 of the calling station to the conductors 67 and 68. The talking connection, as is well known, includes inductive connections which prevent the transmission of loop impulses beyond the exchange 39.

Relay 19 in energizing breaks, through its armature 191 and resting contact, the circuit of relay 12; through its armature 191 and working contact it prepares a locking circuit; through its armature 192 and resting contact it breaks the locking circuit of relays 13, 14, 15, and 16, which de-energize; through its armature 193 and working contact it maintains the left-hand winding circuit of the relay 21 closed through the leads 70 and 71 ending in the private exchange, the circuit having been first completed by the armature 143 of the relay 14; by its armature 192 and working contact it closes the relay circuit 17: earth, armature 192 and working contact, armature 213 and resting contact, armature 221 and resting contact, the winding of relay 17, battery. Relay 17 is a time delay relay of a type such that it only closes its contact after a definite lapse of time. If, for any reasons, the subscriber does not continue the calling process, but replaces his handset, the relay 17, after a certain time, operates armature 171 which completes the circuit of relay 18. Relay 18 is also a time relay of such a kind that after a definite lapse of time it energizes, opening by its armature 181 and resting contact the circuit of relay 19, which deenergizes, thereby disconnecting itself from in bridge of conductors 67 and 68.

The said relay 19 also opens, through its armature 193, the left-hand winding circuit of relay 21, thereby freeing the trunk line comprising the leads 70 and 71; by its armature 192 and working contact the relay 19 breaks the circuit of relay 17, which deenergizes, opening in its turn the circuit of relay 18, which releases. All the apparatus of the secondary exchange, as well as the receiving equipment, Fig. 3, is now in normal position, the line 67—68 is free, and a new call can be received from the public exchange 39.

In addition, by its armature 172, relay 17 closes

the circuit of the calling lamp A_p at the manual switchboard. The operator can listen over the jack J in order to enter into conversation with the calling subscriber and if necessary to direct the communication to another called subscriber of the private exchange.

We will now suppose that the calling subscriber continues the connection operations. Relay 19 being energized, the leads 70 and 71 ending in the automatic secondary exchange have been looped through the left-hand winding of relay 21 . Therefore the automatic switching equipment in the said secondary exchange is ready to effect a connection with a station of the same exchange.

By its armature 194 and working contact the relay 19 also completes the circuit of the leads $67-68$ through the winding 72 of the alternating current impulse receiver.

The calling subscriber, having noted by listening in his receiver that the transmission of ringing current from 39 has ceased, that is to say, that his first connection has been established, works the keys 31 at his station. This opens the contact $31-33$ and closes $31-32$. This results in the relay 10 being energized at each opening of the impulse contacts 37 through the circuit: earth via the equipment of 39 , conductor 43 , closed contact 38 , winding of relay 10 , contact $32-31$, contact $35-34$, lead 40 , lead 42 , and battery via the equipment of exchange 39 . Relay 10 attracts its armature 101 , short circuits, releases, and becomes activated again. It acts therefore in an oscillatory manner. Thus at each opening of the impulse contacts 37 a pulse of alternating current emitted by relay 10 is sent over the line, through the exchange 39 to the leads 67 and 68 , and is received by the winding 72 of the input transformer of a thermionic amplifier through the circuit: lead 68 , armature 111 and resting contact, condenser 77 , armature 211 and resting contact, winding 72 , armature 214 and resting contact, condenser 78 , armature 194 , armature 112 and resting contact to lead 67 .

The alternating current impulses received by the winding 72 induce impulses in the winding 73 , which are amplified by the valve 79 , and rectified by the rectifying system 76 , whereby they operate the relay 23 , which by its armature 232 and resting contact breaks the line circuit of leads 70 and 71 . It can be seen that for every impulse transmitted by the calling subscriber there is a corresponding opening of the line running to the private automatic exchange. The said calling subscriber is thus able to call any of the subscribers attached to the private exchange.

On the receipt of the first numerical impulse, relay 23 closes by its armature 231 the circuit of relay 22 : earth, armature 231 and working contact, winding of relay 22 , and battery. Relay 22 being excited closes, by its armature 222 and working contact, its locking circuit: battery, winding of relay 22 , armature 222 and working contact, armature 192 and working contact, to earth; by its armature 221 it breaks, through its resting contact, the circuit of relay 17 , which de-energizes, and by its working contact closes the circuit of relay 18 : battery; winding of relay 18 , armature 221 and working contact, armature 213 and resting contact, armature 192 and working contact, to earth. As has been already explained, relay 18 is a time delay relay. If the subscriber with whom the calling person wished to communicate does not respond, relay 18 opens its

contact 181 after a certain time which corresponds to the time necessary to effect dialling and ringing, which releases all the apparatus and the calling line as has been already explained.

In the case in which, the calling person having finished the impulsing, the call is completed and the subscriber called replies, the latter produces an inversion of polarity, over the leads 70 and 71 from the private exchange, which energizes the polarized relay 21 . By its armature 212 and working contact it completes a new locking circuit for relay 19 . By its armature 213 it breaks, through its resting contact, the circuit of relay 18 , and closes through its working contact the circuit of relay 20 : battery, winding of relay 20 , armature 213 and working contact, armature 192 and working contact, to earth. Relay 20 energizes, closes through its armature 202 its locking circuit, and breaks by its armature 201 the first energizing and locking circuit of relay 19 .

By its armatures 211 and 214 relay 21 connects leads 67 and 68 with leads 70 and 71 . The calling person is then in communication with the called subscriber. They may enter into conversation or code signals may be transmitted over the line.

At the end of the conversation, or of the recording of signals, a disconnect operation is performed on the line of the called subscriber, as by hanging up, thereby producing a new reversal of the battery through the leads 70 and 71 .

The polarized relay 21 deenergizes. By its armature 212 it breaks the locking circuit of relay 19 thus freeing the line $67-68$ to the public exchange 39 . Relay 19 deenergizes and by its armature 193 breaks the left-hand winding circuit of relay 21 ; the line $70-71$ leading to the private exchange is released. By its armature 192 relay 19 breaks the circuit of relay 22 which is deenergized as well as cutting off the supply of the polarizing winding of 21 . Relay 21 in deenergizing reconnects, by its armatures 211 and 214 , the leads 67 and 68 with the winding 72 of the impulse receiving apparatus.

All the parts of the receiving equipment of the secondary exchange as well as the line leading to the public exchange, and that leading to the private exchange, are now free and in a position to receive or transmit a new call.

On the replacement of the handset by the person calling the line $42-43$ leading to the public exchange is freed in its turn.

We will now explain the method of establishing a direct connection, in the case where a group of calling stations include a voice frequency transmitter which can be connected to any one of the said stations. On consideration of Figure 2 it is seen that the calling station P is connected to a private exchange 80 , which may be an automatic exchange.

By dialling a certain digit the calling person can operate a selector switch in the exchange 80 and connect his line with the transmitter E . At the end of this operation, relay 24 of the transmitter E energizes over the calling line and by its armature 242 and working contact, closes the circuit of relay 25 : battery, non-inductive winding of relay 26 , armature 242 and working contact, winding of relay 25 , to earth. By its armature 241 and working contact relay 24 prepares the seizing and impulsing circuit of line $44-45$, which in this case is connected to line $42-43$ of the public exchange 39 in place of line $40-41$. Relay 75

25, becoming energized in the circuit indicated, completes through its armature 251 and working contact the loop on the output line: lead 42, lead 44, lower right-hand winding of relay 30, 5 lower right-hand winding of relay 29, inductance 28, armature 241 and working contact, armature 251 and working contact, lead 45, to lead 43.

The apparatus of public exchange 39 is thus placed in a condition to receive a call. By its 10 armature 242 and working contact relay 25 completes the circuit of the polarization windings of the polarized relays 29 and 30; by its armature 254 and working contact it prepares the energizing circuit of relay 26; by armature 253 it closes a 15 holding circuit for the operated selector in exchange 39. The calling subscriber, having received dial tone, works his calling dial in accordance with the proper digits, thereby operating automatic switches in exchange 39 to effect 20 the connection of his station with the equipment of Figure 3.

It will be noticed that the energizing windings of the polarized relays 29 and 30 have been placed in series with the loop circuit of the line; the direction of the current in each of these is such that, their polarization being the same, if relay 30 energizes for a definite polarity on the leads 44 and 45, for example a battery on 44, relay 29 on the other hand will not be influenced, and vice versa.

Let us suppose then that relay 30 energizes. By its armature 303 and working contact it closes the circuit of its locking winding, by its armature 304 and working contact it short-circuits its energizing winding; by its armature 301 and working contact it completes the loop circuit which is found open through armature 302 and its resting contact; by its armature 305 it prepares a circuit for the alternating current impulse relay 27.

The breaks made by the dial of station P on the line 81—82 will result in the intermittent de-energizing of relay 24 of E to which the line is connected through the exchange 60. On the 45 reception of the first impulse relay 24 deenergizes and through its armature 242 and resting contact completes the circuit of relay 26; earth, armature 242 and resting contact, armature 254 and working contact, inductive and non-inductive windings of relay 26, to battery (relay 25 whose winding is short-circuited is thus rendered slow to deenergize and remains energized during the whole train of impulses). On becoming energized, relay 26 closes, by its armature 262 and working contact the impulsive circuit: lead 44, armature 262 and working contact, armature 292 and resting contact, armature 241 (which vibrates during the impulses), armature 251 and working contact, to lead 45.

60 Relay 26 remains energized in series with relay 25 during the whole train of impulses. It can be seen that at each deenergization of relay 24 a break is produced, by armature 241, on the line leading to exchange 39. The subscriber P thus accomplishes the orientation of the apparatus of the said exchange, and when the dialling is finished ringing current is sent over the leads 67 and 68 and is received by relay 12 of the apparatus in Figure 3, the operations taking place as they have been described in the preceding case. The line is finally looped with relay 19 which cuts off the ringing current at the exchange 39, and causes the reversal of polarity in the leads 42—43 and 44—45.

75 At the end of the dialling by the subscriber for

the establishment of this second connection relay 24 remains energized as does relay 25.

As soon as the polarity reverses in the line leads 44 and 45 the relay 29 energizes. By its armature 293 and working contact it closes the 5 circuit of its locking winding; by its armature 294 and working contact it short circuits its energizing winding and loops the line through the inductance 28; by its armature 292 and resting contact it breaks the first loop circuit of the 10 line, and by its armature 291 and working contact, it prepares a continuous loop circuit which becomes necessary during the working of relay 24.

The calling subscriber having ascertained, by 15 listening in his receiver, that the call has reached the private exchange of Figure 3, proceeds to a third dialling operation with the object of putting himself directly in communication with a subscriber attached to the private exchange. 20

The impulses are again received by relay 24, but this time the working of the latter is without effect on the apparatus of 39, its armature 241 and working contact being short-circuited by the operated armatures 301 and 291. However, 25 when on the reception of an impulse relay 24 deenergizes, it completes the circuit of relay 27: earth, armature 243 and resting contact, armature 295 and working contact, armature 305 and working contact, winding of relay 27, to battery. 30 Relay 27 becoming energized connects by its armatures 271 and 272 and their working contact the lines 85 and 86 carrying an alternating current of voice frequency with the leads of the line 44 and 45. 35

Thus at every deenergization of the relay 24 there is a corresponding energizing of relay 27 and the transmission over the line of an alternating current impulse.

The said impulses are transmitted through the 40 exchange 39, are received by the apparatus of Figure 3, and effect the establishment of an internal connection as has been described in the preceding case. At the end of this dialling the calling subscriber finds himself in connection 45 with the required station.

The freeing of the apparatus in the called exchange takes place as has already been shown; at the calling exchange, on the replacement of the handset of the person calling, relay 24 de-energizes, causing relay 25 to deenergize after a short time, which opens the circuit of 26 and the locking windings of 29 and 30.

The whole apparatus comes to rest, and the equipment E can be taken up by a new call. 55

The idea of connection through one or more exchanges has been described in the above examples, we will now show the action of an automatic receiving apparatus for impulses capable, on receiving a call, of effecting a visual and audible signal, allowing in particular of the determination of the origin of the call.

The person calling having finished the preceding operations, the apparatus of the public exchange has prepared the connecting circuit, and the call is extended to the apparatus of Figure 3. The ringing current transmitted over the leads 87 and 88 is received by the upper winding of relay 46, which energizes. By its armature 462 and working contact it closes the circuit of its locking 70 coil: earth, armature 471 and resting contact, armature 264 and working contact, lower winding of relay 46, to battery; by its armature 461 it prepares the energizing circuit of relay 47; and by its armature 463 and working contact it closes 75

the circuit of the rotary magnet of finder C1: earth, armature 471 and resting contact, armature 463 and working contact, contact 651 of the electromagnet, winding of electromagnet 65, and battery. The seeker is started in free rotation carrying the wipers 89, 90 and 91.

When wiper 90 arrives at a contact segment such as 90', corresponding to a free registering receiving apparatus, the said wiper finds a battery and the energizing circuit of relay 47 is completed: earth, armature 461 and working contact, the two windings of relay 47 in series, wiper 90, bank contact 90', inductive and non-inductive windings of 60 in parallel, armature 512' and 15 resting contact, contacts 92 and 92' of the switch C2 in its resting position, armature 582 and resting contact, inductive and non-inductive windings of 57 in parallel, to battery. Relay 47 in energizing breaks, by its armature 471 and resting 20 contact, the circuit of the electromagnet 65, ar- resting switch C1; by its armature 471 and work- ing contact it completes its locking circuit through the lower winding; by its armatures 472 and 473 and their working contacts it reconnects 25 the leads 87 and 88 with the wipers 89 and 81; by its armature 471 and resting contact it breaks the circuit of the locking winding of 46, which de- energizes.

Furthermore in the same circuit as 47, relays 60 30 and 57 become energized. Relay 60 on energizing connects by its armatures 601 and 605 and their working contacts the wires of line 87, 88, to relay 52. The emission of the ringing current from exchange 39 comes to an end, and relay 52 35 becoming energized completes the circuit of leads 87 and 88 through the winding 95 of the input transformer of the receiving apparatus for the alternating current impulse.

By its armatures 602, 604 and 606 and their 40 working contacts relay 60 connects the controlling circuits of switches C3, C4, C5 with the bank contacts of switch C2.

Relay 57 on energizing closes, by its armature 571 and working contact, the circuit of the time 45 delay relay 58.

The adjustment of the said relay 58 is regu- 50 lated so that its armature 582 is only operated after the time necessary for the reception and recording of a call has elapsed. After this in- terval it operates its armature 582, opening the energizing circuit of relays 47, 60 and 57 and by the latter its own circuit. The apparatus re- turns to its rest condition and the line from the 55 public exchange is disengaged.

By its armature 572, relay 57 completes the 60 energizing circuit of relay 59; earth, armature 572 and working contact, bank contact 97, wipers of C2, bank contact 96, lower winding of 59, contact 611 of the electromagnet 61, electromagnet 61, and battery.

The resistance of the electromagnet 61 is such 65 that it is not excited in series with 59, which latter, however, becomes energized. By its armature 591 and working contact, relay 59 closes the circuit of the electromagnet 63 of the time stamp 98: earth, armature 572 and working contact, bank contact 97, wipers, bank contact 96, armature 591 and working contact, bank contact 99, wipers, bank contact 100, winding of 63, to bat- 70 tery. The electromagnet 63 attracts its armature 101 producing an impression of the hour and the date on the tape 102.

By its armature 594 and working contact, relay 75 59 completes the circuit of the electromagnet 62 of the mechanism for moving the tape. By its

armature 593 and working contact it places a direct earth on the electromagnet 61 which at- tracts its armature thus breaking the circuit of 59, which deenergizes. Armature 593 opens its contact and the wipers of C2 pass to the second 5 position.

Electromagnets 62 and 63 are deenergized and the tape 102 is advanced, being pulled forward by the rollers associated with 62.

Suppose that the calling subscriber, having 10 ascertained that the transmission of the ringing current from the exchange 39 has ended, con- tinues dialling with the object of indicating, by visual recordings, his own signal or code number, and of exciting an alarm. The transmission of 15 impulses is then made in alternating current, as has been shown in the previous examples. The said impulses received by the leads 87 and 88 are transmitted by the circuit: lead 87, arma- ture 473 and working contact, wiper 89, bank 20 contact 89', armature 601 and working contact, input winding 95 of amplifier A2, armature 605 and working contact, bank contact 91', wiper 91, armature 472, and working contact, and lead 88, to the grid of the amplifier; are amplified 25 and retransmitted through induction coil 93; and after passing through the rectifier 94, they activate the impulse relay 53.

On the reception of the first impulse, relay 53 30 closes, through its armature 531 and working 35 contact, the circuit of relay 54 which becomes energized. By its armature 541 and working contact, relay 54 closes the energizing circuit of relay 55: earth, armature 541 and working contact, ar- mature 551 and resting contact, the lower winding 35 of 55, to battery; by its armature 542 and work- ing contact it closes the circuit of the stepping electromagnet 66 of the recording drum 95 which attracts its armature causing the said drum to 40 advance one space.

Relay 55 on energizing completes, by its arma- ture 553 and working contact, the circuit of relay 56, which becomes energized; by its armature 554 it closes the circuit of the electromagnet 61 45 of switch C2 which attracts its armature.

Relay 55 is found to be short circuited every 50 time 54 deenergizes, and being thus rendered slow locks itself throughout the whole of the reception of the impulse train.

By its armature 541, relay 54, on the reception 55 of each impulse of the first train of impulses, causes the step by step advancement of the switch C5 of the lamp recorder over the circuit: earth, armature 541 and working contact, bank contact 104 of C2, wiper of C2 in the second position, bank contact 103, armature 606 and work- ing contact, winding of electromagnet 50, and battery.

It can be seen that, at the end of the first 60 train of impulses, the switch C5 and the number 60 drum, 95 will have advanced a number of steps equal to the number of impulses received. When the impulses cease relay 55 deenergizes.

By retracting its armature 554, relay 55 breaks 65 the circuit of the electromagnet 61 which releases its armature, stepping the wipers of C2 to the third position. The retraction of armature 554 of relay 55 also closes a circuit for magnet 62, since the slow acting relay 56 remains in oper- ated position for an instant after 55 falls back. 70 Relay 55 on retracting its armature 553 closes a circuit for magnet 64. The operation of magnet 64 prints on the tape 102 the digit set up on number drum 95. Shortly after relay 55 deener- 75 gizes, relay 56 deenergizes, breaking the circuits

of magnets 64 and 62. The latter magnet advances the tape 102 when it deenergizes.

The deenergization of 56 also restores the number drum by completing the circuit: armature 553 and resting contact, armature 561, resting contact, off normal contact 106, interrupter contact of electromagnet 66, magnet 66, and battery. Magnet 66 vibrates its armature, whereby drum 95 is moved forward automatically to its position of rest, in which it breaks the contact 106 causing it to stop at the said position.

It can be seen that after the reception of the first impulse train, the corresponding number has been printed on the tape 102, and the switch C5 of the lamp recorder occupies a position corresponding to the number of impulses received. Also the circuit of electromagnet 49 of switch C4 has been prepared to receive the impulses of relay 54 as has been explained in the case of the advancement of switch C5.

The impulses of the second train take the wipers of the said switch C4 to the position corresponding to the number of impulses emitted. At the end of the second train, roller 95 prints the corresponding digit as has been explained in the preceding case, and switch C4 stops. On the deenergizing of relay 55, switch C2 advances to the fourth position. The third train of impulses will now be received by the switch C3 which takes up a position corresponding to the number of impulses received. The third digit is printed on the tape 102.

It has been assumed in the example given that the recorder is arranged to receive calling signals of three digits. It is clear that the number of switches such as C3, C4 and C5 could be increased by providing control circuits attached to the vacant contact segments of switch C2, and one could thus receive calls of four digits and upwards.

After the reception of the third train of impulses relay 55 deenergizes causing the advance of switch C2 to the fifth position. The circuit of relay 51 is completed through: earth, armature 572 and working contact, contacts and wipers of C2 in the fifth position, armature 603 and working contact, winding of 51, and battery. Relay 51 in energizing locks itself at its armature 512 and closes, by its armature 511, 513 and 514 and their working contacts, the circuits of the signal lamps of the recorder, which thus indicate the number of the calling station.

By its armature 515 and working contact it closes the audible alarm circuit including bells such as 107; by its armature 516 and working contact it closes the circuit of relay 51' which energizes, breaking, by 512' and resting contact, the circuit of relays 41, 60 and 57, which deenergize. By its armature 511' and working contact it closes its locking circuit through the middle wipers of C3, C4 and C5.

Relay 47 opens the line circuit to the public exchange 39; the said line is free and can receive a new call.

65 Relay 60 deenergizing frees the call recorder, and prepares the return circuits of switches C3, C4, and C5, for advancing said switches to their resting position. Relay 57 opens by its armature 571 and working contact, the circuit of time relay 70 58. By its armature 572, and resting contact, it completes the circuit of relay 59: earth, armature 572, resting contact, bank contacts 108 and 109 of C2, upper winding of 59, contact 611 of electromagnet 61, electromagnet 61, and battery.

75 By its armature 593 and working contact, the

relay 59 closes the circuit of electromagnet 61 which attracts its armature and at 611 breaks the circuit of 59, which deenergizes, but becomes energized again as soon as contact 611 is re-closed. It can be seen that the switch C2 automatically advances, controlled by relay 59; when the said switch reaches its resting position the circuit of 59 is broken.

During the restoration of C2 relay 59 transmits impulses to magnet 62 at armature 592. Magnet 62 accordingly advances the tape 102 by means of rollers 111 and 112.

When the call has been noticed, the operator at the exchange works key 113 which deenergizes relay 51, which by its armatures 511, 513 and 514 and their resting contacts, completes the circuits for the automatic return to the resting position, of switches C3, C4 and C5. When the said switches have all three returned to their resting position, the locking circuit of relay 51' is opened, and this relay deenergizes.

The call recording apparatus is now in a position to receive and record a new call.

In the explanations referring to the working of the apparatus which has just been described, it has been assumed that the control impulses were sent out by the calling person by means of a dial. It is clear that one could use any apparatus capable of sending a convenient code of impulses, without the action of the system being affected, and in particular could use the automatic impulse-sending apparatus shown in Figures 4, 5, 6 and 7, whose working will now be explained.

Referring to Figure 4, in which only those parts of the apparatus necessary for understanding the invention have been included, it is seen that the apparatus comprises five cams 10, 11, 12, 13, and 14 mounted on the same shaft.

These cams may be set in rotary motion by a driving system not represented, whose velocity is regulated by the governor 15. The impulse cam 16 is also set in motion by the same driving system.

In the rest position the compound arm 20 of the armature of the polarized relay 19 is engaged in the notch 24 of the disc 10, thus holding the mechanism stationary.

If now Figure 7, which represents the scheme of electrical connections of the impulse sender, is examined, it is seen that a certain number of contacts such as 25 and 26 are distributed at the various points from which a call might have to be sent. Leads 27 and 28 go to an ordinary telephone station and leads 29 and 30 to a public automatic exchange. Furthermore, the impulse sending system may be inserted in the telephone line by means of a quadruple jack represented in Figure 7.

Let us suppose that a person works the calling button 25. The following circuit is completed: lead 29, spring 31, spring 32 (of cam 11 in Figure 4), closed contact 25, winding of relay 19, impulse springs 17-18, and lead 30.

Relay 19 is energized through the equipment of the public exchange and attracts its armature in the position shown in Figure 6 in full lines. Arm 20 is thus disengaged from the disc 10 and the mechanism is set in motion, including cams 10, 11, 12, 13 and 14, the governor 15 and the impulse cam 16. Cam 12 works spring 37 and by its contact 38 short-circuits relay 19; after a short interval, necessary for putting the apparatus of the exchange in a position to receive the call, the cam 11 operates its contact springs. By its spring 34 it breaks at contact 33 the circuit of 75.

the station connected to leads 27 and 28; by its springs 34 and 35, it loops leads 29 and 30 with the calling apparatus; by spring 32 it breaks the circuit of the calling buttons, at contact 31.

5 Line 29-30 being in a position to receive the call, cam 13 operates spring 39 and opens the circuit of its resting contact 39. Thereupon the impulse springs 17-18 are no longer short-circuited and under the influence of cam 16, can 10 send, during the whole time that the control spring 44 of cam 13 is in the notch 43, a series 15 of impulses which will be received by the public exchange.

Cam 13 continues its rotation and the part 45 15 again operates the control spring 44, and by springs 39 and 40 short circuits the impulse springs 17 and 18. After a short interval a new notch in cam 13 effects the transmission of another train of impulses, as has been shown.

20 It can be seen that during half a revolution of cam 13, for the shape represented, by way of example, three trains of impulses will have been sent over leads 29 and 30, the said impulses effecting the orientation of the apparatus of the 25 exchange to complete the call to the subscriber dialled.

When the cams have rotated through half a revolution, the compound pin 46 of cam 10 comes to rest on arm 22 of the plate 21, which occupies 30 the position shown in full lines in Figure 6, as has been shown. This holds up the mechanism and the cams stop. Spring 37 associated with cam 12 is released in notch 47 which has taken up a position diametrically opposite to that shown in 35 the figure. Polarized relay 19 is no longer short circuited. Spring 44 now rests on the projecting portion 48 of cam 13.

When the call is completed at the receiving station, it produces at the public exchange, reversal 40 of polarity in leads 29 and 30. Polarized relay 19 again operates its armature and attracts parts 21 and 20. 21 frees the pin 46, but its displacement is limited by 20 which comes to rest against the cam 10. Under these conditions the arm 23 of the said part 21 will not be able to engage the pin 46 placed symmetrically on the other face of cam 10, and the freed mechanisms are set in motion again and with them the cams. Cam 12 operates its spring 37 and short-circuits polarized relay 50 19. Cam 14 frees its spring 49, which comes to the cut-away portion of the said cam, which brings about the closing of the circuit of springs 41 and 42 and prepares an energizing circuit for relay 50.

55 It can be seen that when, by the action of the profile of cam 13, spring 39 opens its circuit with contact 40, relay 50 is placed in parallel with the impulse springs 17 and 18.

At each opening of the said springs, relay 50 60 energizes and by vibratory action of its armature 51 emits an impulse of alternating current.

The result is that this second series of impulses will be emitted as alternating current impulses and will be received via the public exchange at the 65 private exchange called where it will effect the orientation of the alarm or call recording apparatus as has been explained in the preceding cases.

When the second impulsing has been finished, 70 cam 10 having completed one revolution, the pin 52 comes to rest against arms 23 of piece 21 (Figure 6) in the position shown in dotted lines. The mechanism stops. Cam 11 whose control spring is again opposite the incised portions, operates its 75 contacts. The loop over the line 29-30 is

broken, and the circuit of the calling buttons is put into action again. Polarized relay 19 returns to its conditions of rest, and 20 engages in the notch 24 holding the mechanism locked after freeing the pin 52 by arm 23 of piece 21. A new 5 call can be sent over the line.

It will be noticed that the action of the mechanism is independent of the initial polarities of the line, one or other of the pins such as 46 being used at the moment of reversal of the current, 10 the action remaining the same as that already described.

Having described the invention, what is considered to be new and is desired to be protected by Letters Patent will be set forth in the following claims.

What is claimed is:

1. A telephone substation comprising a calling device, impulse springs in said calling device adapted to be bridged across the line, a relay, 20 means including off-normal contacts of said calling device for causing said relay to be shunted around said impulse springs during the operation of the calling device, and contacts on said relay for short circuiting its winding. 25

2. In a repeater, incoming and outgoing lines, a line relay responsive to loop impulses received over its incoming line for repeating loop impulses over the outgoing line, and means controlled over said outgoing line for changing the circuits 30 of the repeater so that said relay responds to loop impulses received over the incoming line by repeating alternating current impulses over said outgoing line.

3. In a switching system, an impulse transmitter, means for operating said transmitter to send trains of impulses of a particular character, automatic switches responsive to said impulses to partially establish a desired connection, means revertively controlled over the partial 40 connection for altering the transmitter so that further operation thereof will produce trains of impulses of a different character, and switches for completing the connection responsive to such last mentioned impulse trains. 45

4. In a switching system, a trunk line extending through a repeater to an automatic switch, means in said repeater for converting alternating current impulses to operate said switch into loop impulses, and means responsive to ringing current 50 received over said trunk line for connecting up said converting means.

5. In a switching system, a trunk line extending through a repeater to an automatic switch, means in said repeater for converting impulses 55 of high frequency alternating current into loop impulses to operate said switch, and means in said repeater responsive to a predetermined number of impulses of low frequency alternating current for connecting up said converting means. 60

6. In a switching system, a repeater, incoming and outgoing lines, means responsive to impulses of high frequency alternating current received over said incoming line for repeating loop impulses over said outgoing line, automatic switches 65 responsive to said loop impulses to complete a connection and means in the repeater revertively controlled over said outgoing line responsive to completion of the connection for connecting together the said incoming and outgoing lines. 70

7. In a telephone system, two automatic exchanges, automatic switches in the first exchange controlled by loop impulses to set up a talking circuit including an inductive connection, a trunk line leading to the second exchange adapted 75

to be included in said connection, means for transmitting alternating current impulses through said inductive connection and over said trunk line to the second exchange, switches in the second exchange controlled by loop impulses, and means for converting alternating current impulses into loop impulses to operate said switches.

8. In a telephone system, a repeater adapted to transmit either loop impulses or alternating current impulses, means responsive to trains of loop impulses transmitted by said repeater for extending a connection, means responsive to the extension of said connection as far as it can be accomplished by means of loop impulses for automatically converting said repeater to the transmission of alternating current impulses, and means for further extending the connection responsive to alternating current impulses.

9. In a telephone system, a repeater adapted to transmit either loop impulses or alternating current impulses, trunk lines over which loop impulses can be transmitted, other trunk lines over which alternating current impulses but not loop impulses can be transmitted, means responsive to trains of impulses emitted by said repeater for setting up a connection by linking together a plurality of said trunk lines, and means effective when a trunk line over which loop impulses cannot be transmitted is linked into the connection for automatically changing over said repeater to cause the same to transmit alternating current impulses.

10. The combination, with an automatic exchange, of a repeater controlled over a subscriber's line for sending trains of loop impulses to said exchange, a line, automatic switches responsive to said impulses to connect with said line, a recorder on said line, means responsive to the completion of said connection for altering said repeater so that alternating current impulses may be sent over the established connection to said recorder, and means for operating said

recorder responsive to said alternating current impulses.

11. The combination, with an automatic exchange, of a plurality of lines that can be called through said telephone exchange, a plurality of recorders common to said lines, means responsive to the receipt of a call on one of said lines for connecting the same to an idle recorder, and means for transmitting alternating current impulses over the established connection to operate 10 said recorder.

12. In a telephone system, a line, a recorder controlled over said line, a connector, a repeater, means including said repeater for transmitting loop impulses to operate said connector to connect with said line, means in the connector for sending ringing current over the line to said recorder, and means in the recorder for controlling the connector to cut off the ringing current and also for causing the connector to control the 20 repeater and condition the same to transmit alternating current impulses through the connector to operate the recorder.

13. In an automatic impulse transmitter, means for transmitting a plurality of trains of 25 impulses of a certain character, means automatically effective after part of said trains have been sent for altering the transmitter so that the succeeding trains will comprise impulses of a different character, and means for automatically 30 restoring the transmitter to its former condition after all said trains have been sent.

14. In an automatic impulse transmitter, impulse springs intermittently opened and closed, a circuit, means including a cam for rendering 35 said springs effective at spaced intervals to open and close said circuit, a relay having contacts for short circuiting itself, and means including another cam for bridging said relay around said contacts during certain of said intervals.
